HEATING APPARATUS

Robert J. Parsons, Schenectady, and John W. Conway, Mechanicville, N. Y., assignors to Consolidated Car-Heating Company, Inc., Albany, N. Y., a corporation of New York

Application October 28, 1931, Serial No. 571,644

8 Claims. (Cl. 237—12.3)

For a detailed description of the present form of our invention, reference may be had to the following specification and to the accompanying drawing forming a part thereof, wherein

5 Fig. 1 represents diagrammatically our invention and

Fig. 2 shows a modification.

Our invention involves a low-pressure steam heating system particularly adapted for heating 10 motor cars and one that uses a small amount of water.

Referring to Fig. 1, F represents the exhaust pipe of the car-driving engine, which pipe serves as the source of heat for the system. Pipe F is 15 enlarged at A to form a boiler, consisting of a coil of pipe, the left hand part of said coil being shielded by an inside pipe G to cause a lesser degree of vaporization in the shielded turns, amounting at times to a condensation for a purpose to be explained later. From the right hand 20 end of the boiler a pipe c, containing a stop cock H, leads to the right hand or lower end of the inclined radiator B. This radiator consists of a pipe, provided with external radiating fins, and 25 slightly inclined so as to go under a car seat. At its upper left hand end the radiator is provided with any well known type of thermostatic vent valve conventionally illustrated at E, so as to 30 vent air and water therefrom. From the high end 35 of the radiator contiguous to the valve E a water-return pipe d leads to a small water reservoir C. The reservoir C is sealed at its top by means of a small pipe coil D, the outer end of which is open to the atmosphere. Said coil will permit 40 the escape of air from the reservoir, but steam will be condensed within the coil, so that the condensate will be returned to the reservoir. The 45 coil is of such length that the accumulation of condensate therein will be sufficient to prevent escape of live steam to the atmosphere through the coil. From the bottom of reservoir C a pipe b leads to the left hand end of the boiler, which 50 is also connected by pipe a, to the right hand end of radiator B. The aforesaid shield G serves to form a water trap at the shielded part of boiler A, by preventing vaporization until the condensate has traveled to the unshielded portion. The 55 only pressure that can exist in boiler A is that required to balance the water head in reservoir C and pipes a and b. That pressure is about one half a pound, rising occasionally to one pound. Assuming that the boiler marked A is cold and is filled with water from the reservoir C: When 60 heat is supplied, steam will be formed and will force the water out of the boiler through the

65 pipes a, b and c. Steam will thereupon find its way into the radiator B, through the pipes a and c and when it has reached the higher end of said radiator B, it will act on the valve E and effect closure of said valve. Condensate forming 70 within the radiator B will collect in the lower end of the radiator and flow into the pipe a, because the pipe c enters the radiator at a position higher than the position that pipe a communicates with the radiator. As the circulation is 75 created the water of condensation in the pipe a as well as water in pipe b enters the end of the boiler which is shielded as indicated at G. By reason of the shielding engagement the hottest 80 part of the boiler will be the unshielded portion 85 and normally steam will not be generated until the water reaches said unshielded portion. The steam as generated will pass upwardly through pipe c, because there will be some resistance to 90 its passing out of the other end of the boiler 95 on account of the water and condensate having collected at that end. Pipe d is a supplemental 100 return pipe and functions as such only when the grade or angle of the radiator B has been 105 changed, due to the vehicle being on a grade, or 110 at such times as there is not enough heat supplied to the boiler to generate sufficient steam to 115 satisfy the demand. In this latter case, the upper 120 end of the radiator often cools off and the 125 thermostatic valve E will open. When heat is 130 again applied to the boiler, water is sometimes 135 pushed to the upper end of the radiator and is 140 discharged through E, until it becomes hot enough 145 to be closed. The purpose of the shield G is to 150 prevent formation of steam in the shielded portion 155 of the coil; thus insuring that the steam 160 will leave the boiler through the pipe c and that 165 the condensate will return to the boiler through 170 pipe a. The shielded portion of the boiler runs 175 cooler than the other end, because the boiler 180 coils in the shielded end are protected from direct 185 contact with the hot gases and this shield therefore 190 stabilizes the action in the boiler. Steam 195 only leaves the boiler through pipes a and c 200 when heat is first applied, but after the radiator 205 commences to function the pipe a constitutes the 210 return pipe from the radiator under normal operating 215 conditions. Pipe d is a supplemental return pipe 220 but functions only during the starting period 225 or during the abnormal operation, as explained 230 above. Eventually the water in the system 235 will fall below the level e, which may be 240 considered the normal level, but the heating 245 will go on until the water in the pipes is 250 exhausted. Till that occurs there will be water 255

in the pipes at the point X and when such exhaustion happens, replenishment is called for.

The arrangement in Fig. 2 is the same, except that we have added what we term a percolator 5 K, which consists of a small reservoir interpolated between pipe b and the reservoir C. That portion of the pipe indicated at b² passes down below and up through the exhaust pipe F at L. The heating effect of the exhaust pipe at L is 10 sufficient to give a slight pumping effect to accentuate the upward flow of water through b² into K. That is, the steam bubbles produced at L in pipe b² will rise up in b² carrying water with them which discharges in K. When the engine is 15 shut down, the only water that can flow back into the boiler, apart from the condensate in radiator B, is the small amount of water which may be contained in the percolator K. The body of water in C and K and the intermediate pipe 20 b² thus constitutes a separate body, but when the engine starts, the pumping effect at L is sufficient to start a circulation through the boiler. The described percolator K causes a more rapid starting of the heating action after the engine 25 has been temporarily stopped, say at a red light. It is to be understood that in practice, the radiator normally occupies the position illustrated in the drawing, and that the return pipe d is so arranged, in each instance, as to drain condensate from the normally high end of the radiator 30 during the periods that the radiator is temporarily inclined oppositely to its normal inclination during travel of the vehicle.

What we claim as new and desire to secure by 35 Letters Patent is:

1. In a vehicle heating apparatus, a radiator constructed and arranged to be normally disposed in a horizontally inclined position with one end higher than the other, a boiler, supply and return 40 pipes connecting spaced apart positions of the boiler with the lower end of the radiator at different levels, and supplemental return means connecting the higher end of the radiator with the return pipe at a position between the boiler 45 and the radiator, in such manner as to drain condensate from the normally higher end during periods that the radiator is inclined oppositely to its normal inclination.

2. In a vehicle heating apparatus, a radiator 50 constructed and arranged to be normally disposed in a horizontally inclined position with one end higher than the other, a boiler, means shielding a portion of the boiler and so constructed and arranged as to prevent vaporization at the shielded portion, a supply pipe connecting the unshielded portion of the boiler with the lower end of the radiator, a return pipe connecting the shielded portion of the boiler with the lower end of the radiator, but at a level lower than the 55 connection of the supply pipe with the radiator, and supplemental means connected with the higher end of the radiator and also with said return pipe at a position between the boiler and the radiator, in such manner as to drain condensate from the normally higher end during periods that the radiator is inclined oppositely to its 60 normal inclination.

3. In a vehicle heating apparatus, a radiator 70 constructed and arranged to be normally disposed at a horizontally inclined position with one end higher than the other, a boiler, a reservoir located at a higher level than said boiler, supply and return pipes connecting spaced apart positions of the boiler with the lower end of the radiator at different levels, a supplemental return 75

pipe connecting the higher end of the radiator with said reservoir, in such manner as to drain condensate from the normally higher end during periods that the radiator is inclined oppositely to its normal inclination and means connecting the 5 reservoir with said return pipe at a position between the boiler and the radiator.

4. In a vehicle heating system, a radiator constructed and arranged to be normally disposed in a horizontally inclined position, a boiler, a reservoir located in a higher plane than that of the boiler, a tubular coiled seal for the reservoir having one end discharging into the atmosphere, a return pipe connecting the higher end of the radiator with the reservoir, in such manner as to 10 drain condensate from the normally higher end during periods that the radiator is inclined oppositely to its normal inclination, a supply pipe and a second return pipe both connected to the lower end of the radiator, with the supply pipe 15 connection in a higher plane than that of the last-mentioned return pipe connection, the other ends of said supply and second return pipe being respectively connected to opposite ends of the boiler, and a pipe connecting said reservoir with said 20 second return pipe at a position between the boiler and the radiator.

5. A vehicle heating system comprising a radiator constructed and arranged to be normally disposed in a horizontally inclined position, a boiler, 30 means by which the boiler may be heated by the exhaust gases of an internal combustion engine, a water reservoir located in a higher plane than the boiler and connected with the higher end of the radiator, in such manner as to drain condensate from the normally higher end during 35 periods that the radiator is inclined oppositely to its normal inclination, a supply pipe connecting one end of the boiler with the lower end of the radiator, and a return pipe connecting the other 40 end of the boiler with the lower end of the radiator but in a lower plane than that of the connection of the supply pipe therewith, and a supplemental return pipe connecting the reservoir with the first-mentioned return pipe at a 45 position between the boiler and the radiator.

6. A vehicle heating system comprising a radiator constructed and arranged to be normally disposed in a horizontally inclined position, a boiler including a helical coil, and means for heating the same, means for shielding a portion of said coil from the heating means, a gravity water reservoir located in a higher plane than that of the boiler, a pipe connecting the higher end of the radiator with said reservoir, in such 55 manner as to drain condensate from the normally higher end during periods that the radiator is inclined oppositely to its normal inclination, a supply pipe connecting the unshielded end of the boiler with the lower end of the radiator, a return pipe connecting the lower end of the radiator with the shielded portion of the boiler, the connection of the return pipe with the radiator being in a lower plane than that of the connection between the supply pipe and the radiator, and a supplemental return pipe connecting the reservoir with the first-mentioned return pipe at a position between the radiator and the boiler.

7. A heating system of the character described comprising a radiator disposed in a horizontally 70 inclined position, a boiler having means constructed and arranged to effect heating thereof by means of the exhaust gases of an internal combustion engine, a main water reservoir connected with the higher end of the radiator for 75

receiving condensate therefrom, a supply connection leading from one end of the boiler to the lower end of the radiator, a return connection leading from the lower end of the radiator to the other end of the boiler, the return connection with the radiator being in a lower plane than that of the supply connection, a supplemental water reservoir located at substantially the same level as said main reservoir, and having a pipe connected therewith, said pipe connection being so constructed and arranged as to be heated by the exhaust gases, and opening into said supplemental reservoir at a position above its connection with said main reservoir, and a supplemental return pipe connecting the supplemental reservoir to the first-mentioned return connection at a position between the boiler and the radiator.

8. A heating system of the character described comprising a radiator disposed in a horizontally

inclined position, a boiler, two water reservoirs in approximately the same horizontal plane but in a higher plane than that of the boiler, a supply pipe connecting one end of the boiler with the lower end of the radiator, a return pipe connecting the other end of the boiler with the lower end of the radiator but in a lower plane than the connection of said supply pipe with the radiator, a pipe connecting the higher end of the radiator with one of said reservoirs, a supplemental return pipe connecting the other reservoir with the first mentioned return pipe at a position between the radiator and the boiler, a pipe connecting the two reservoirs, and opening into one reservoir at a position above its connection with the other reservoir, and means for heating the last-mentioned pipe.
